CLAIM

The ornamental design for an electronic control device, as shown and described.

DESCRIPTION

FIG. 1 is a front view of an electronic control device showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
